UNITED STATES PATENT OFFICE

CORNELIUS S. BONNE, OF ROCKFORD, ILLINOIS

ELASTIC SHOE LACE

Application filed August 26, 1929. Serial No. 388,824.

My invention relates to new and improved shoe fasteners for replacing the cloth laces of the type now generally in use. The invention is adapted for use with all types of shoes having eyelets or openings for laces.

The shoe laces now in common use comprise essentially a cloth non-elastic braid or string having metal tips to facilitate insertion into the holes of the shoe. When shoes are laced about the foot with this type of lace there is no opportunity for the shoe to expand even slightly with the movement of the foot. If it is urged forward suddenly as in running or jumping it comes against the front or laced part of the shoe and is stopped abruptly many times injuring the arch. If the lace breaks in one place all of the strands loosen and the entire lace must be replaced immediately. The laces are slow and cumbersome in lacing and knots are constantly coming loose.

One of the objects of the invention is the provision of an elastic shoe lace which will permit the shoe top to assume and snugly keep the contour of the upper foot assuring foot comfort at all times.

Another object is the provision of a shoe lace with which the shoe may be rapidly laced and unlaced.

I have also aimed to provide a shoe lace which will permit the upper part of the shoe to expand and contract with the swelling or contraction of the foot.

Other objects and attending advantages will be seen by those skilled in the art from the following description and the drawings in which:

Figure 1 is a perspective view of a shoe embodying my invention;

Fig. 2 is a section of the upper part of a shoe showing a lace in place; and

Fig. 3 is a side view of the subject-matter of my invention.

The lace may be said to consist of three parts: the disc-like base 5, the lace 6, and the tip 7. In the preferred form all three parts are made from a single piece of rubber or made separately and vulcanized together. The base is made from a rather hard and firm rubber which will not easily be distorted.

Its purpose is to form a permanent anchor-

age for the lace, the end 7 being inserted in the eyelet and the lace 6 drawn through until the base comes firmly against the underside of the eyelet. The base should therefore be made from a sufficiently hard and firm rubber composition that it will not be drawn through the eyelet. The lace 6 is made from a tough and elastic rubber and is of sufficient length to hold the tip firmly against the side of the eyelet 8. The tip is made from a hard unelastic rubber and has a hook shape to hold it firmly in its eyelet under the tension of the elastic lace. The rubber used in preparing the laces is given various colors to correspond with the color of the shoes with which they are to be used. The number of laces to be used with each shoe will correspond to the number of pairs of eyelets in the shoe.

In use the tip 7 is inserted in the eyelet 9 and the lace 6 drawn through until the base 5 rests firmly against the underside of the eyelet 9. The lace is then stretched while the tip is inserted in the eyelet 8. The tension on the lace will cause the tip to remain in the eyelet until it is removed by releasing the tension. This may be done by grasping the lace 6 and exerting a slight pull in the direction of the tip. It will be seen that the operation of the laces is very easy and rapid. After they are once inserted the sole movements necessary to lace and unlace the shoe is the removal of the top from the eyelet or the insertion of the tip therein.

While I have thus described and illustrated my invention I am aware that numerous changes may be made without departing from the spirit of the invention and I do not desire to limit it except by the spirit of the invention and the appended claims.

I claim:

1. In an elastic shoe lace the combination of an elastic lace portion, a disc base portion and a curved tip portion.

2. In an elastic shoe lace for shoes having eyelets the combination of an elastic portion, means for preventing one end of said elastic portion from passing through an eyelet and means for holding the opposite end of said elastic portion within the opposite eyelet.

3. A one piece elastic shoe lace for shoes

having eyelets comprising a disc-like rubber base portion, an elastic rubber body portion and a hard rubber inwardly disposed tip portion adapted to hook through an eyelet of the
5 shoe.

In witness of the foregoing I affix my signature.

CORNELIUS S. BONNE.
